UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

Application filed September 8, 1921, Serial No. 499,209. Renewed February 18, 1923.

To all whom it may concern:

Be it known that I, JOHN F. O'CONNOR, a citizen of the United States, residing at Chicago, in the county of Cook and State 5 of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

One object of the invention is to provide 15 an efficient draft gear.

Other specific objects will appear from a complete description of one embodiment of the invention hereinafter following.

In the drawing, to which reference is 20 hereinafter made, Figure 1 is a horizontal sectional view in part plan of a draft rigging embodying the invention. Figure 2 is a cross-section taken on line 2—2 of Figure 1. Figure 3 is a cross-section taken on line 25 3—3 of Figure 1. Figure 4 is a partial longitudinal sectional view taken on line 4—4 of Figure 3. Figure 5 is a similar section taken on line 5—5 of Figure 3. Figure 6 is a perspective view of the spring follower 30 employed in the gear. Figure 7 is a perspective view of one of the wedge elements. And Figure 8 is a perspective view of one of the friction elements.

In the drawing, the numerals 10—10 indicate draft members or parts of the car frame to which the draft rigging is applied. The butt of the coupler is shown at 11, having a usual coupler key 12, by means of which it is slidingly connected, as at 13, to 40 the draft yoke 14. Usual front and rear stops are shown respectively at 15 and 16. 17 indicates a front follower; 18 a shell, 19 a supporting tie or carrier plate, secured in a manner well understood, to the draft members. Within the shell are mounted the 45 spring elements 20 and a wedging system 21. The wedging system includes the central wedged element 22 and the lateral wedge elements 23—23, the latter being provided 50 with the outer anti-friction roll seats 24—24 and the inner anti-friction roll seat 25, each provided with an anti-friction roller 26. On either side of the wedging system there is 55 mounted a set of friction plates comprising the longitudinally fixed plates 27 and the

movable plates 28 alternately arranged, as plainly disclosed in Figures 1, 2 and 3. The plates 27 are provided each with upper and lower lugs 29 adapted to enter the upper and lower internal transverse grooves 30 provided in the shell, which permit their lateral movement in respect to the wedging system, and when actuated thereby prevent their longitudinal movement. Rearwardly the 60 said plates are provided with slots 130 which members, upon the spring follower herein-after described, enter. The spring follower as a whole, is indicated by the numeral 31 and comprises the plate 32 against the rear face of which the springs members are seated. Near either end lugs or guides 33 are forwardly extended from its front face and are adapted to enter and slide within the 65 slots 130 in the plates 27. Intermediate its ends the spring follower includes the block- 70 like portion 34, the hollow interior 35 of which receives the block 40 which is a retaining member shouldered in the shell 18 and borne against by the head 36 of the connecting bolt 37 carrying the nut 41 held in 75 the wedge 22, all of which makes movable connection between the elements of the wedging system and the said spring follower. The spring follower is further provided with the upper flange 38 and the lower 80 flange 39 vertically spaced apart sufficiently to embrace the elements of the wedging system, which, when mounted and in normal position of the parts has its outer spring 85 seats 32 within the space defined by the 90 flanges 38 and 39 of the follower so that the ends of the anti-friction roll terminate between the plates 38 and 39 of the spring follower and are held thereby against accidental endwise removal. The anti-friction 95 rollers operate between the wedge elements and the adjacent friction plates 28. By reason of the construction of the spring follower a simple and efficient means is provided for the retention of the anti-friction 100 rollers in their proper position.

I have herein shown and described what I now consider the preferred manner of carrying out the invention, but the same is merely 105 illustrative and I contemplate all changes and modifications that come within the scope of the claims appended hereto.

I claim:

1. In a friction shock absorbing mechanism, having friction, spring and wedging 110

elements, including anti-friction members associated with said wedging elements, the combination therewith of a spring follower having a pair of flanges embracing the wedging elements and forming stops for the ends of the anti-friction rollers.

2. In a friction shock absorbing mechanism, spring and friction elements, in combination with a wedging system and a spring follower, the wedging system having anti-friction members therein, the spring follower having a pair of flanges opposing the anti-friction members at their ends.

3. In a friction shock absorbing mechanism, the combination with friction and spring elements, of a wedging system therefore and a spring follower, the wedging system comprising spreading and anti-friction elements, the spring follower having a pair of flanges embracing the wedging system and forming endwise stops for the anti-friction elements.

4. In a friction shock absorbing mechanism, the combination with friction members

and springs, of a spring follower and a wedging system, the wedging system including a spreading element and anti-friction members mounted between said spreading element and the friction element, the spring follower having anti-friction element retaining flanges embracing the wedging system.

5. In a friction shock absorbing mechanism, the combination with friction members and springs, of a spring follower and a wedging system, the wedging system including a spreading element and anti-friction members mounted between said spreading element and the friction element, the spring follower being provided with upper and lower flanges forming retaining members for the said anti-friction member.

In witness that I claim the foregoing I have hereunto subscribed my name this 31st day of Aug., 1921.

JOHN F. O'CONNOR
